UNITED STATES PATENT OFFICE.

ALBERT D. HEYL, OF NEW YORK, N. Y., ASSIGNOR TO QUIGLEY FURNACE AND FOUNDRY COMPANY, A CORPORATION OF MASSACHUSETTS.

PULVERIZED-FUEL-FEEDING DEVICE.

1,145,894.

Specification of Letters Patent. Patented July 13, 1915.

Application filed September 23, 1914. Serial No. 863,216.

To all whom it may concern:

Be it known that I, ALBERT D. HEYL, a citizen of the United States of America, residing at New York city, county and State 5 of New York, have invented certain new and useful Improvements in Pulverized-Fuel-Feeding Devices, of which the following is a specification.

My invention relates to apparatus for 10 feeding finely divided material, such as pulverized coal which is delivered to furnaces upon a current of air.

It constitutes an improvement on the type 15 of apparatus shown and described in patent to J. V. Culliney, No. 784,307, dated March 7, 1905. In pulverized coal feeders or controllers of this type the coal dust is fed out from under a hopper at a regular 20 rate by a screw conveyer and over an opening into an air conduit chamber, into or through which it drops, and in which it meets a transverse current of air entering at one side and passing out at the other. The desired quantity of fuel is carried away on 25 this transverse air current, while the surplus, if any, falls to a lower conduit, where a return screw conveyer forces such surplus back to the hopper. In the patented form 30 of apparatus above described the rate of delivery to the air conduit chamber is constant for a given rate of rotation of the feed screw, and the only way in which such rate of delivery can be varied is by changing the driving gears, or the speed of the motor 35 driving the screws. Either of these is a matter of some difficulty under certain conditions, and usually only gives a step by step adjustment. As a result, any finer adjustment of the amount of fuel carried away 40 by the air blast must be secured by regulating the volume or speed of the air current itself. This makes two adjustments necessary to secure the full range of regulation.

My invention reduces the matter of such 45 regulation or control of the fuel to the movement of a single gate, leaving both the conveyer screws and the air blast to operate at constant rates.

The best form of apparatus embodying 50 my invention at present known to me, and one modification thereof, are illustrated in the accompanying sheet of drawings in which,

Figure 1 is a side elevation and partial

vertical section (with parts broken away) of 55 a controller of the Culliney type modified to operate according to my improved method. Fig. 2 is a cross section taken on line 2—2 of Fig. 1. Fig. 3 is a detail section on the plane of Fig. 1, showing a modification, and Fig. 60 4 is a cross section on the same plane as Fig. 2, also showing said modification.

Throughout the drawings like reference characters indicate like parts.

1, is the hopper from which the feed screw 65 2, draws a quantity of pulverized coal along the feed conduit 3. In the under side of this conduit, at the far end, is an opening to the vertical passageway 4, which communicates with the lower, and upwardly inclined return conduit 5, in which is the return screw conveyer 6. The gearing 7, causes the two screw conveyers to revolve in opposite directions. The passageway 4, is always open. I will call it the surplus chamber. The magazine, or hopper, constituting the source of supply, the two conduits and conveyer mechanism therein, and the surplus chamber, constitute a closed circuit or path 70 for the circulation of the pulverized coal or 75 other material, which is constantly open, and of a capacity to handle the maximum quantity ever required.

The air conduit chamber 8, is next to the surplus chamber, on the side toward the 85 hopper 1. This has its opening 9, from the bottom of feed conduit 3, controlled by gate 10. When the gate is open the chamber 8, constitutes a by-pass across the closed path 90 of circulation above described. The transverse air current enters this chamber 8, by pipe 11, and passes out by pipe 12.

In operation the conveyer screws are run at a constant speed sufficient to deliver the maximum quantity of coal which can be 95 handled, and the air blast is also supplied at a rate and pressure sufficient to handle the maximum quantity which can be delivered to it by the conveyer 2. If now the gate 10, be opened wide, the full quantity 100 of coal delivered by the feed screw 2, will fall into the air conduit chamber 8, and practically all of this will be carried away through discharge conduit or pipe 12, and delivered to the furnace. If the gate 10, be 105 closed, all of the coal will be carried on to the surplus chamber 4, through which it will drop to the return screw conveyer 6.

Having, therefore, described my invention, I claim:

40

1. In an apparatus for feeding finely divided material the combination of a hopper, a feed conduit and a return conduit extending from said hopper, conveyer screws therein, a surplus chamber connecting the two conduits, an air conduit chamber connected to the feed conduit between the hopper and the surplus chamber, and an adjustable gate controlling such connection to the air conduit chamber.

45

2. In an apparatus for feeding finely divided material the combination of a source of supply, a feed conduit extending therefrom, a return conduit connected to the feed conduit by a permanently open passageway and leading back to the source of supply, continuously acting conveying means in said conduits, a by-pass connecting said conduits located between the permanently open passageway and the source of supply, conveying means connected with said by-pass, and mechanism for controlling the opening between the feed conduit and the by-pass.

50

3. In an apparatus for feeding finely divided material the combination with mechanism for circulating a given quantity of material through a constantly maintained closed circuit of fixed capacity, of a by-pass across said circuit, conveying means connected with said by-pass, and means for adjusting the opening to said by-pass.
